CLAIM

The ornamental design for a universal stand for cue cases, as shown and described.

DESCRIPTION

FIG. 1 is a top front perspective view of a universal stand for cue cases showing my new design;

FIG. 2 is a bottom front perspective view thereof;

FIG. 3 is a top rear perspective view thereof;

FIG. 4 is a front view thereof;

FIG. 5 is a rear view thereof;

FIG. 6 is a left view thereof;

FIG. 7 is a right view thereof;

FIG. 8 is a top view thereof;

FIG. 9 is a bottom view thereof; and,

FIG. 10 is a top view of a universal stand for cue cases wherein two arms and a flexible strap are shown in an alternate position.

The universal stand for cue cases is shown with a symbolic break in its height. The appearance of any portion of the article between the break lines forms no part of the claimed design.
